REFRIGERATOR OR THE LIKE

Robert W. Schier, Royal Oak, and Montgomery Ferar,
Huntington Woods, Mich., assignors to Whirlpool-
Seeger Corporation, St. Joseph, Mich., a corporation of Delaware

Application October 13, 1955; Serial No. 38,354

Term of patent 3½ years

(Cl. D67—3)

Fig. 1.

Fig. 3.

Fig. 5.

Fig. 4.

Fig. 6.

Fig. 2.

Fig. 7

Fig. 1 is a perspective view of a refrigerator or the like showing our new design;

Fig. 2 is a front elevational view of the handle and escutcheon plate shown in Figure 1;

Fig. 3 is an end elevational view of Fig. 2;

Fig. 4 is a bottom plan view of the handle;

Fig. 5 is a cross-sectional view taken on line 5—5 of Fig. 3;

Fig. 6 is a cross-sectional view taken on line 6—6 of Fig. 3;

Fig. 7 is a bottom plan view of Fig. 3.

The essential features of our design reside in the portions shown in full lines.

We claim:

The ornamental design for a refrigerator or the like, substantially as shown and described.
